UNITED STATES PATENT OFFICE.

EMIL BOMMER, OF NEW YORK, N. Y.

SPRING-HINGE.

1,131,660.

Specification of Letters Patent.

Patented Mar. 16, 1915.

Application filed April 15, 1913, Serial No. 761,141. Renewed July 15, 1914. Serial No. 851,227.

To all whom it may concern:

Be it known that I, EMIL BOMMER, a citizen of the United States of America, residing in New York, in the borough of Brooklyn, county of Kings, and State of New York, have invented certain new and useful Improvements in Spring-Hinges, of which the following is a specification.

This invention relates to certain improvements in single-acting spring-hinges of that class in which one leaf is bent up integrally with the barrel from a single blank of sheet-metal, the leaf thus bent up consisting of two layers which are formed of extensions 15 of the barrel and which are rigidly connected with each other.

The invention will be more fully described hereinafter and finally pointed out in the claims.

20 In the accompanying drawing, Figure 1 represents a rear-elevation of my improved single-acting spring-hinge, Fig. 2 is a horizontal section of the same on line 2, 2, Fig. 1, and Figs. 3 and 4 are respectively a detail 25 section showing the upper portion of the barrel and its leaf, and a side-elevation of the same, drawn on an enlarged scale, Fig. 5 represents a partly bent-up blank, showing the upper and lower extensions and 30 screw-holes for connecting the layers of the web, and Fig. 6 is a horizontal section on line 6, 6, Fig. 5.

Similar letters of reference indicate corresponding parts throughout the several figures of the drawing.

Referring to the drawing, *b* represents the barrel, *d* the flanged leaf of the spring-hinge, which is made of a single thickness of sheet-metal and provided with perforated 40 ears *d*¹ bent up at right angles to the leaf, and *d*², a reinforcing flange extending between the ears vertically along the inner edge of the flanged leaf *d*. The pintle *p* passes through the perforations of the ears *d*¹, the 45 center of the barrel *b*, the adjustable spring-holder *c*, its bushing *e*, and the fixed spring-holder *c*¹ and its washer *e*¹. From the barrel *b* extend two overlapping layers *b*¹, *b*² which are, like the leaf *d*, provided with 50 screw-holes, the thickness of the two layers of the barrel-leaf together corresponding approximately to the thickness of the flanged leaf *d*. The two layers *b*¹ and *b*² of the barrel-leaf *a* extend above and below the upper and lower edges of the barrel, up to a level with the upper and lower edges of the

ears *d*¹ of the flanged leaf *d*. The upward and downward extensions of the layer *b*¹ of the barrel-leaf *a* are wider than the upward and downward extensions of the layer *b*² 60 and are slightly nicked or slotted, as at *r*, adjacent to the upper and lower edges of the barrel, the greater width of the upward and downward extensions of the inner layer *b*¹ serving to provide sufficient stock for the 65 flaps *r*¹ and for bending the same around the adjacent recesses *r*² in the edges of the extensions of the layer *b*² and for clenching the edges *r*¹, *r*² of the two layers *b*¹ and *b*² into rigid connection with each other flush 70 into the plane of the connected layers *b*¹ and *b*² of the barrel-leaf *a*. The layer *b*² is recessed at the edge *r*² of its upward and downward extensions to receive the bent edge *r*¹ of the layer *b*¹ which is reduced in 75 thickness at the bend. The screw-holes *b*³ for attaching the spring-hinge to the door consist of smaller holes in the layer *b*², which holes correspond in location with the larger holes in the layer *b*¹, the holes of the 80 layer *b*² being made smaller than the diameter of the screw for which they are intended, the surplus stock, shown by dotted lines in Figs. 1 and 5, around the smaller holes *b*³ of the layers *b*² being then thrown up in 85 forward direction into the larger perforations *b*³ of the layer *b*¹ and upset into the same so as to form screw-holes of the required size and shape for the shanks and heads of the screws. By thus upsetting or 90 swaging the surplus stock at the screw-holes *b*³ of the layer *b*² in an opposed direction to the clenched connection of the inner edges *r*¹, *r*² of the upper and lower extensions of the two layers *b*¹ and *b*², a reliable 95 rigid connection of the two layers of the barrel-leaf *a* of the spring-hinge is obtained, by making use of integral parts of the layers for connecting them together and overcoming thereby the use of separate rivets 100 and the objectionable appearance given by them to the leaf.

I claim:

1. In a spring-hinge, a barrel provided with a leaf bent up in two layers integrally with the barrel, said layers having extensions, one extension having its edge adjacent to the barrel bent and clenched around the other extension at its edge adjacent the barrel. 105

2. In a spring-hinge, a barrel provided with a leaf consisting of two layers bent up 110

integrally with the barrel, both layers being provided with extensions above and below the upper and lower edges of the barrel, the extensions of the first layer being wider than 5 the extensions of the second layer for being bent and clenched over the second layer, and screw-holes in both layers, the screw-holes of the second layer being of smaller diameter than the screw-holes of the first layer, 10 the stock forming the difference in size of the screw-holes being upset into the screw-holes of said first layer in a direction oppo-

site to the bent and clenched edges of the extensions of the first layer over the second layer, for rigidly connecting the layers together. 15

In testimony, that I claim the foregoing as my invention, I have signed my name in presence of two subscribing witnesses.

EMIL BOMMER.
